APPARATUS FOR THE DISTILLATION OF FATTY ACIDS, GLYCERIN, AND THE LIKE

Filed Nov. 12, 1924

Wilhelm Gensecke Inventor

By James Townsend & Bruckenstein
his Attorneys.

UNITED STATES PATENT OFFICE.

WILHELM GENSECKE, OF BAD HOMBURG, GERMANY.

APPARATUS FOR THE DISTILLATION OF FATTY ACIDS, GLYCERIN, AND THE LIKE.

Application filed November 12, 1924, Serial No. 749,565, and in Germany November 28, 1923.

Fatty acids, glycerin and similar materials are usually distilled by means of superheated steam (steam distillation) and it is known that in such processes the employment of 5 subatmospheric pressure is advantageous. It is therefore customary to connect the distilling vessel through a surface condenser for the fatty acid, glycerin or the like, and a water cooled condenser for the steam with 10 a gas pump for creating and maintaining a partial vacuum in the distilling apparatus. The extent to which the pressure in the distilling vessel in this arrangement of apparatus may be reduced and maintained is thus 15 limited to the vapor pressure which of course depends upon the temperature of the water in the steam condenser.

According to the present invention the distillation is carried out under a pressure 20 which is less than the vapor pressure of the water in the steam condenser. By operating under a lower pressure the distilling temperature is correspondingly reduced, the quality of the distillation product is im- 25 proved, and steam and heat are saved. These results are accomplished by placing a gas pump between the distilling vessel and the steam condenser with its suction side communicating with the distilling vessel and 30 its pressure side communicating with the condenser. The gas pump is preferably located between the surface condenser and the steam condenser. A pump of the steam jet type is particularly well adapted for this 35 purpose because it has no moving parts and is capable of handling a large volume of gas without mechanical difficulties. One form of apparatus suitable for carrying out the process of my invention is illustrated in 40 the accompanying drawing.

Referring to the drawing, *a* is the distilling vessel, *b* a pipe for the introduction of superheated steam into the material to be distilled, *c* a surface condenser which serves 45 to condense the fatty acids, glycerin or the

like, and *d* a water cooled steam condenser. The liquid separated from the distillation gases in the condenser *c* collects in the trap *e* and is discharged through the vessel *f*. Between the condenser *c* and the condenser *d* 50 is the pump *g* of the well known steam jet or injector type supplied with steam through the pipe *l*. The steam employed in the pump *g* as well as the steam passing therethrough from the condenser *c* are condensed in the 55 condenser *d*. The condenser *d* is of the jet or spray type having a water supply pipe *h* and a hydrostatic leg *m*. Uncondensed gas such as air is removed from the condenser *d* through the liquid trap *i* and pipe *k* by 60 means of an air pump (not shown).

I claim:

1. Apparatus for the steam distillation of fatty acids, glycerin and the like under high vacuum, comprising a distilling vessel, a surface condenser for the fatty acids, glycerin and the like, communicating with said distilling vessel, a water cooled steam condenser and a steam operated injector compressor, having its suction side in communication 65 with said surface condenser for the fatty acids, glycerin and the like, and its pressure side in communication with said steam condenser.

2. Apparatus for the steam distillation of fatty acids, glycerin and the like under high vacuum, comprising a distilling vessel, a surface condenser for the fatty acids, glycerin and the like, communicating with said distilling vessel, a water cooled steam condenser, a steam operated injector compressor, having its suction side in communication 70 with said surface condenser for the fatty acids, glycerin and the like, and its pressure side in communication with said steam condenser, and a liquid trap between the surface condenser and the injector for collecting the condensate from the surface condenser.

In testimony whereof, I affix my signature.

WILHELM GENSECKE.
